ELECTRICAL DISCHARGE DEVICE

Charles Spaeth, Flushing, N. Y., assignor to
Ne-Arga Corporation, Jersey City, N. J., a corporation of New York

Application October 23, 1930. Serial No. 490,646

2 Claims. (Cl. 176—125)

This invention relates to electric discharge lamps, and more particularly to lamps of the type described in my copending application, filed even date herewith, in which the color spectrum radiated by the lamp is controlled by means of a reservoir of mercury from which mercury vapor is introduced into the lamp proper at a predetermined rate.

In accordance with the disclosure forming part 10 of said pending application, the vaporization of the mercury is controlled by means of an auxiliary electrode immersed therein, the current flow from the positive side of the line (connected with the anode) being controlled in turn by a 15 variable resistance. In operating lamps of this type I have found that under certain conditions the lamp may become unstable. I have found, for instance, that where the line voltage is subject to sudden variations, it becomes difficult to control the color of the lamp. In case there is a 20 sudden increase in the line voltage, more than the required quantity of mercury vapor is introduced into the lamp proper, causing it to turn bluish. Furthermore, owing to the presence of 25 more than the required mercury vapor in the lamp, the latter draws a great deal of current and may cause the burning out of resistances. In case there is a sudden drop in line voltage, less than the required quantity of mercury vapor 30 is produced, the lamp turns reddish (assuming that it contains neon), its internal resistance increases and the lamp may even go out.

In order to obviate these drawbacks, in accordance with the present invention, the auxiliary electrode, by means of which the mercury 35 or the like is heated, is connected through a variable resistance with the negative instead of the positive side of the line. When so connected the lamp burns steadily and emits a predetermined spectrum without regard to the 40 usual line voltage variations.

The invention is more clearly set forth in the following detailed description and the drawing in which Figs. 1, 2, 3, 4 and 5 illustrate schematically five embodiments of the invention. 45 Throughout the drawing, corresponding elements bear the same reference numerals.

Referring now to Fig. 1, 1 is a glass envelope or tube containing the usual filling of rare or 50 monatomic gas, such as neon, an anode 2 and an alkaline metal cathode 3. A reservoir 4 containing a pool of mercury 5 is connected with the tube 1. The anode 2 is connected through a fixed resistance 6 with the positive side of the line (supplying say, 220 v. D. C.), and the cath-

ode is connected with the negative side of the line. An auxiliary electrode 7 immersed in the pool of mercury 5 is connected through a variable resistance 8 with the negative or cathode side of the tube.

Owing to the shortness of the path between the auxiliary electrode 7, which is now negative, and the anode, a discharge between the two can easily be produced, and once the lamp is operating in the manner described in my co-pending application, it will radiate the predetermined spectrum which remains constant even where the line voltage varies as much as plus or minus 30 v.; that is to say, with a lamp designed to operate on 220 v. D. C., its characteristics will remain constant at from 190 v. to 250 v.

In the arrangement shown in Fig. 2, the auxiliary electrode 7 is connected through a rather coarse filament of tungsten wire 9 with the positive side of the tube. In the normal operation 75 of the device, the tungsten filament 9 glows at a dull red color and will aid in the vaporization of the mercury. I have found that lamps constructed in accordance with this embodiment start very easily, even where the passageway between the reservoir and the main envelope is restricted or screened to keep out the liquid mercury. Owing to the fact that the heating circuit of the mercury is bridged across the input circuit of the lamp, it becomes a relatively simple matter to adjust 80 the arrangement for any desired operating characteristics.

A modification of the last mentioned arrangement is shown in Fig. 3 in which the tungsten filament 9 is connected with the anode side of 90 the tube through the tubing which links the reservoir 4 with the anode chamber.

In the arrangement shown in Fig. 4, the auxiliary electrode 7 is connected with the negative side of the tube and the variable resistance 8, also 95 provided in the negative connection of the tube, connects with one end of the tungsten filament 9.

Referring now to Fig. 5, we have the same type of lamp as above described. However, heating current for the auxiliary electrode 7 and the tungsten filament 9 is supplied from a source of 110 v. A. C. through the usual variable resistance 8 and a transformer 10. The auxiliary electrodes and tungsten filaments of a number of other tubes 105 (all like the one shown), indicated at 9^a and 9^c, are connected in parallel with the auxiliary electrodes of tube 1 and are thus supplied with heating current from a common source.

Obviously, other modifications and embodied 110

ments may be practiced within the spirit of the present invention.

What is claimed is:

1. In an electric discharge device, a light transmitting envelope, a rare gas filling in said envelope, an anode and a cathode within said envelope, a reservoir containing mercury connected with said envelope near said anode, an auxiliary electrode immersed in said mercury, a filament 10 within said reservoir and connected at one end with said auxiliary electrode, a source of current, a connection from the positive side of said source to said anode, a fixed resistance in said connection, a connection from the other side of 15 said filament with said connection at a point between the anode and said resistance, and a variable resistance connected between said auxiliary electrode and the negative side of said source.

2. In an electrical discharge device, an envelope, a filling of neon gas within the envelope, said filling being adapted when ionized to give off light, an anode and a cathode, the cathode comprising an alkaline metal for passing a discharge through said gas, a reservoir, said reservoir containing mercury, the mercury being adapted to give off vapor capable of modifying the color value of said rare gas, auxiliary means comprising a variable resistance connected in series with the mercury and the negative side of the current supply, the mercury constituting a cathode and establishing a flow of current from said anode to the mercury contained in said reservoir.
